(57) **CLAIM**

The ornamental design for a trailer hitch for attaching a towing rope, as shown and described.

DESCRIPTION

FIG. 1 is a right rear perspective view of the trailer hitch for attaching a towing rope of the present invention;

FIG. 2 is a top plan view thereof;

FIG. 3 is a right side elevational view thereof, the left side elevational view being a mirror image thereof;

FIG. 4 is a bottom plan view thereof; and,

FIG. 5 is a front elevational view thereof.
